WEFT CARRIER FOR WEFT-REPLENISHING LOOMS

Application filed April 3, 1929. Serial No. 352,291.

This invention relates to weft carriers for weft replenishing looms wherein a fresh supply of weft is furnished the shuttle from time to time during the loom operation.

It is now the usual practice to provide weft replenishing looms with a hopper or magazine for the support of the weft carriers and their movement to transferring position. In looms of this type it is essential that the shuttle be automatically threaded as the shuttle is picked, and it has been the practice for the weaver to find the end of the weft, unwind it from the carrier and secure it to a fixed point which has been generally constituted as a 10 stud at the end of the hopper. As a consequence of securing the end of the weft as stated, the shuttle becomes partially threaded on the first pick following replenishment.

Since the weaver is called upon to find the 20 end of the weft on the wound carrier as he places the carriers in the hopper or magazine, much valuable time is lost in finding the end of the weft because it clings tightly to the wound surface as it comes from the spinning 25 frame. One of the objects of the present invention is to facilitate the weaver's work as he places the filled carriers in the hopper or magazine and grasps the weft end to secure it to the weft end stud to insure shuttle thread- 30 ing.

In accordance with the present invention the weft carrier is provided with a weft end holder formed as a spring which may clamp the weft end against the tip portion of the 35 carrier with the result that as the weaver withdraws the projecting end of the weft for attachment to the weft end stud, the weft end holder will be grasped by the weaver and removed longitudinally of the weft carrier, so 40 that the weft carrier may be readily placed in the magazine or hopper freed from the weft end holder.

The work of finding the weft end and clamping it to the tip of the weft carrier by 45 means of the weft end holder may be readily accomplished at a point remote from the loom and by cheap labor, with the result that the work of the weaver and cost of cloth production are materially reduced.

50 In accordance with the present invention

the weft end holder is constituted as a spring of somewhat less diameter than the tip of the weft carrier and is provided with an opening at one side whereby it may be applied over the tip of the weft carrier in a transverse direction and thus clamp or secure the weft end ready for the weaver's manipulation. 55

The invention and novel features thereof will best be made clear from the following description and accompanying drawings of 60 one good practical form thereof.

In the drawings:—

Fig. 1 is a perspective view of a hopper or magazine showing more particularly how the weaver may manipulate and withdraw the 65 weft end from the weft carrier as he also removes the weft end holder.

Fig. 2 shows a weft carrier wound with weft and the end of the weft drawn endwise of the weft carrier, with the weft end holder 70 positioned for application to the tip of the weft carrier.

Fig. 3 is a view similar to that of Fig. 2 but showing the weft end holder in place on the tip of the weft carrier and clamping the projecting end of the weft ready to be grasped by the weaver. 75

The hopper or magazine for holding the fresh supplies of weft may be of usual type and as herein shown consists of a stand 1 mounted upon the loom frame as usual and supporting the rotary hopper which may consist of the disk 2 for holding the head portions of the weft carriers, and a somewhat similar disk 3 for holding the tip end portions of the 85 weft carriers.

The stand 1 has extending therefrom the stud 4 on which is mounted the transerrer 5 normally under the influence of a spring 6 for maintaining it in upward or inactive 90 position, and extending from the hub portion of the transerrer is the arm 7 to which may be pivoted at 8 the transerrer dog 9, herein shown as engaged with a bunter 10 on the lay 11, for imparting to the transerrer 95 its transferring movement as usual in this class of looms.

The rotary hopper has a supporting stud or shaft 12 on which is mounted the weft end stud 13 to which the weft ends are secured by 100

the weaver as he fills the hopper or magazine with a fresh supply of weft carriers. As usual in this class of hoppers or magazines, there may be the guides 14 for directing the weft ends of the weft carriers in the hopper or magazine.

The weft carrier consists of a barrel portion as usual having a head 15 which may be supplied with the rings 16 for detachable engagement with the bobbin holding springs in the shuttle. When the weft carrier is supplied with weft, as indicated at 17, and comes from the spinning frame, the weft end is carried spirally about the wound weft and clings closely thereto so that much difficulty is experienced and loss of time and expense incurred when the weaver himself tries to find the weft end to attach it to the weft end stud in the hopper.

A wound weft carrier, as indicated in Figs. 2 and 3, has the weft wound thereon in conical layers which have been gradually laid towards the tip end portion of the weft carrier leaving an exposed tip 18, and, in accordance with the present invention, the weft end holder is constituted as a spring 19 of general circular form having a side opening 20 of less width than the diameter of the weft carrier tip, with the result that the weft end holder may be applied about the tip and over the withdrawn weft end *a* which has previously been found and extended by the employment of cheap labor and before the weft carrier reaches the loom.

When the weft end holder is applied to the tip of the weft carrier as indicated in Fig. 3, the spring weft end holder clamps the extended end *a* of the weft upon the surface of the tip and when the weaver receives the weft carriers in the condition indicated in Fig. 3 he may grasp with one hand the wound weft carrier, as indicated at *b*, Fig. 1, then grasp by his other hand as *c* both the weft end *a* and the weft end holder 19, and withdraw both simultaneously lengthwise of the weft carrier.

Under these conditions it will be apparent that the weaver has only to grasp the weft carrier with one hand and the weft end holder and weft end with the other hand and secure the end of the weft to the weft end stud 13, thus saving his time and securing the parts in proper position for replenishment and threading of the shuttle.

The weft end holder 19, as hereinbefore stated, is of general circular form and of slightly less diameter than the diameter of the tip portion of the weft carrier, with the result that the spring action of the weft end holder serves not only to maintain it on the tip of the carrier, but also to yieldingly clamp the withdrawn end *a* of the weft.

It is desirable that the weft end holder 19 shall not only have the opening 20 in its side, but that the terminal portions of the weft end

holder 19 as at 21 and 22 be flared outwardly so that the weft end holder may be readily applied about the tip of the weft carrier and over the withdrawn weft end *a*.

Claims:—

1. A weft carrier for weft replenishing looms having a head portion and a tip, and a weft end holder constituted as a curved spring having a side opening of less width than the tip diameter that the holder may be transversely applied about the tip and over the weft end and manually removed endwise of the tip as the weft end is withdrawn for attachment to a fixed part.

2. A weft carrier for weft replenishing looms having a head portion and a tip, and a weft end holder formed as an open sided curved spring for clamping the weft end upon the tip and manually removable endwise of the tip as the weft end is withdrawn to be attached to a fixed part.

3. A weft carrier having a head portion and a tip to be held in the hopper of a weft replenishing loom, and a weft end holder constituted as a curved spring of less interior diameter than the diameter of the carrier tip to yieldingly hold the weft end clamped upon the tip and manually removable endwise of the tip with the weft end as it is withdrawn for attachment to the weft end stud.

In testimony whereof, I have signed my name to this specification.

CLARE H. DRAPER.
